CLAIM

I claim the ornamental design for a lantern, as shown and described.

DESCRIPTION

FIG. 1 is a front perspective view of a lantern in accordance with a second embodiment of the present invention.

FIG. 2 is a left side view of the lantern of FIG. 1.

FIG. 3 is a right side view of the lantern of FIG. 1.

FIG. 4 is a front view of the lantern of FIG. 1.

FIG. 5 is a rear view of the lantern of FIG. 1.

FIG. 6 is a top view of the lantern of FIG. 1; and,

FIG. 7 is a bottom view of the lantern of FIG. 1.

The broken lines show features which form no part of the claimed design.
